UNITED STATES PATENT OFFICE

133,788

DESIGN FOR AN AUTOMOBILE EXHAUST SHROUD

Louis A. Koch, Louisville, Ky.

Application January 12, 1942, Serial No. 105,123

Term of patent 7 years

To all whom it may concern:

Be it known that I, Louis A. Koch, a citizen of the United States, residing at Louisville, in the county of Jefferson and State of Kentucky, have invented a new, original, and ornamental Design for an Automobile Exhaust Shroud, of which the following is a specification, reference being had to the accompanying drawings, forming a part thereof.

In said drawings:

Figure 1 is a top plan view of an automobile exhaust shroud showing my new design;

Figure 2 is a perspective view of the shroud of Figure 1;

Figure 3 is a side elevational view of the shroud of Figure 1; and

Figure 4 is a bottom plan view of the shroud of Figure 1.

I claim:

The ornamental design for an automobile exhaust shroud, as shown.

LOUIS A. KOCH.
